UNITED STATES PATENT OFFICE.

ISSAC A. WATROUS, OF WEST HAVEN, CONNECTICUT, ASSIGNOR OF ONE-HALF TO FRANK F. BURTON, OF NEW HAVEN, CONNECTICUT.

AUTOMATIC ELECTRIC REVERSE-SWITCH.

No. 839,348.

Specification of Letters Patent.

Patented Dec. 25, 1906.

Application filed May 7, 1906. Serial No. 315,581.

To all whom it may concern:

Be it known that I, ISSAC A. WATROUS, a citizen of the United States, residing at West Haven, in the county of New Haven and State of Connecticut, have invented a new and useful Improvement in Automatic Electric Reverse-Switches; and I do hereby declare the following, when taken in connection with the accompanying drawings and the numerals of reference marked thereon, to be a full, clear, and exact description of the same, and which said drawings constitute part of this specification, and represent, in—

Figure 1, a broken view in elevation showing a portion of a gas-engine to which my improved switch has been applied, the fly-wheel of the engine being shown in section; Fig. 2, a broken view in inside elevation of the fly-wheel; Fig. 3, a detached view of the switch with its cover removed; Fig. 4, a view showing the circuit-breaker held in its open position by the trigger.

My invention relates to an improved automatic electric reverse-switch for internal-combustion engines, the object being to provide simple, convenient, and reliable means for the purpose indicated.

With these ends in view my invention consists in the construction to be hereinafter described, and pointed out in the claims.

In carrying out my invention as herein shown I employ a circuit-breaker 2, having the general form of a bell-crank lever and hung upon a screw-stud 3 within a switch-box 4, having a cover 5, this box being provided with a bracket 6, having a hole 7 for the reception of a bolt 8, by means of which the switch is rigidly fastened to the engine-base 9. The contact-arm 2^a of the circuit-breaker 2 normally makes contact with a terminal plate 10, secured by a binding-screw 11 to an insulating-block 12, fastened by a screw 13 to the bottom of the box 4. A return-wire 14 leads from the binding-screw 11 to the source of the current, whatever that may be. The other arm 2^b of the circuit-breaker 2 carries a steel trigger-blade 15, coacting with a corresponding trigger-blade 16 in the arm 17 of a bell-crank trigger 18, hung within the said box upon a screw-stud 19, its arm 20 projecting through an opening 21 in the side of the box 4 and furnished with a segmental trigger-shoe 22, arranged to be engaged by a hub-like tripper-weight 23, located at one end of a tripper 24, hung upon a screw-stud 25, entering the web 26 of the fly-wheel 27. Of course the tripper might be pivoted to a spoke of the fly-wheel in case the fly-wheel were of spoked construction. A tripper-spring 28, secured at one end to the fly-wheel by means of a screw 29, is provided at its opposite end with a hook 30, adapting it to be engaged with any one of a series of notches 31, formed along the outer edge of the long arm of the tripper, whereby the spring may be adjusted in position to change its pull on the tripper, as may be required. An adjusting-screw 32, mounted in the short arm of the tripper 24, engages with the inner periphery of the fly-wheel and provides for adjustably limiting the movement of the tripper-weight 23 toward the trigger-shoe 22. For the manual operation of the circuit-breaker I provide its arm 2^b with a finger 33, connected by a wire 34 with a bell-crank lever 35, which is connected by a wire 36 with a bell-crank lever 37, which is connected by a wire 38 with a manual of any approved character, such as an ordinary bell-pull 38^a. A spring 39, connected with the bell-crank lever 37, overcomes any tension that may be left on the wire 38, and so relieves the tension on the spring 40, which tends to hold the circuit-breaker in contact with the terminal plate 10, while the spring 41, connected with the trigger, holds the blade 16 thereof in readiness to be reengaged with the blade 15, carried by the circuit-breaker, these springs 40 and 41 being located within the switch-box 4, as seen in Fig. 3. Normally the circuit-breaker is in contact with the terminal plate 10, as seen in Fig. 3. Normally also the trigger-blade 16 has its inner face engaged with the end of the trigger-blade 15. The spring 28 is adjusted upon the tripper 24, as it will also be understood with respect to the speed of the fly-wheel 27, so that the action of centrifugal force will normally hold the hub-like tripper-weight 23 out of engagement with the tripper-shoe 22. Now when it is desired to reverse the engine the bell-pull 38^a or other manual is operated to swing the circuit-breaker 2 against the tension of its spring 40, whereby the circuit is broken and the edge of the trigger-blade 16 engaged with the upper face of the trigger-blade 15. The circuit-breaker is thus temporarily locked, so to speak, in its open position. The circuit

having been broken, no more electricity will be transmitted to the sparker of the engine, the explosions of which will cease, and therefore the fly-wheel 27 will slow down. As the fly-wheel goes slower and slower the action of centrifugal force will be proportionately reduced, and the tripper-spring 28 will assert itself to draw the hub-like tripper-weight 23 toward the tripper-shoe 22, which will be engaged, whereby the tripper will be swung against the tension of its spring 41 and the blades 15 and 16 disengaged, whereupon the circuit-breaker spring 40 will assert itself to return the circuit-breaker to its normal position, as shown in Fig. 3, so that the circuit will be again closed to the sparker of the engine, with the difference, however, that the circuit will be closed just before the crank of the engine reaches the top of the stroke instead of just after the top of the stroke is reached, which is the usual thing. The circuit being closed and the sparking being re-established on the opposite side of the stroke, so to speak, the engine will reverse. It should be explained in this connection that in order to effect the reversal of an engine of this character the resumption of sparking must be done by closing the circuit at a carefully predetermined time and place. This it is difficult to do by any method so "hit or miss" as the manual insertion of an electric plug under the guidance of the movement of a fly-wheel as seen by the eye. Under my invention, however, the spring 28 and the screw 32 may be adjusted with reference to the normal speed of the engine to such a nicety that the tripper 23 will act upon the trigger-shoe 22 at precisely the point required for resuming the sparking in such a way as to cause the reversal of the engine. After the manual 38 has been operated the engagement of the tripper-blades 15 and 16 holds the circuit-breaker in position to keep the circuit open until the tripper operates in the manner described.

I claim—

1. In an automatic electric reverse-switch for internal-combustion engines, the combination with a circuit-breaker, of a trigger coacting therewith to hold the circuit-breaker in its open position, and a spring-controlled tripper applied to the fly-wheel of the engine and adapted to coact with the trigger to release the circuit-breaker for the closing of the circuit at a predetermined time and place. 55

2. In an automatic electric reverse-switch for internal-combustion engines, the combination with a pivotal circuit-breaker, of a trigger coacting with the circuit-breaker and provided with a trigger-shoe, a tripper pivotally mounted upon the fly-wheel of the engine and formed with a weight to coact with the trigger-shoe, and an adjustable spring connected with the tripper for controlling the action thereof whereby the tripper operates the trigger to release the circuit-breaker at a predetermined time and place. 6c

3. In an automatic electric reverse-switch for internal-combustion engines, the combination with a pivotal circuit-breaker carrying a trigger-blade, of a pivotal trigger carrying a trigger-blade to coact with the trigger-blade specified and also carrying a trigger-shoe, a tripper pivotally mounted upon the fly-wheel of the engine and adapted to coact with the trigger-shoe, and a spring mounted upon the fly-wheel and adjustably connected with the tripper whereby the spring may be set with reference to the tripper to cause the same to act upon the trigger to release the circuit-breaker and close the circuit at a predetermined time and place. 70

In testimony whereof I have signed this specification in the presence of two subscribing witnesses.

ISSAC A. WATROUS.
